UNITED STATES PATENT OFFICE.

RUSSELL D. GEORGE, OF BOULDER, COLORADO.

PROCESS FOR CRACKING OILS.

1,420,832.

Specification of Letters Patent. Patented June 27, 1922.

Application filed September 14, 1921. Serial No. 500,510.

To all whom it may concern:

Be it known that I, RUSSELL D. GEORGE, a citizen of the United States, residing at Boulder, in the county of Boulder and State 5 of Colorado, have invented certain new and useful Improvements in Processes for Cracking Oils, (for which I have filed applications in Argentina, Oct. 25, 1920; Australia, Oct. 14, 1920; Austria, Sept. 25, 1920; Bel- 10gium, Sept. 23, 1920; Brazil, Sept. 30, 1920; Canada, Sept. 10, 1920; Chile, Oct. 25, 1920; Colombia, Feb. 3, 1921; Cuba, Sept. 29, 1920; Czecho-Slovakia, Sept. 27, 1920; Ecuador, 15; Egypt, Oct. 4, 1920; France, Sept. 21, 1920; Germany, Sept. 25, 1920; Great Britain, Sept. 14, 1920; Holland, Sept. 14, 1920; Hungary, Sept. 29, 1920; India, Nov. 1, 1920; Italy, Sept. 27, 1920; Jamaica, Oct. 20, 1920; Japan, Sept. 29, 1920; Mexico, 20 Sept. 21, 1920; Panama, Nov. 10, 1920; Peru, Dec. 16, 1920; Poland, Sept. 24, 1920; Rumania, Sept. 29, 1920; Spain, Sept. 27, 1920; Trinidad and Tobago Nov. 15, 1920; Turkey, Oct. 14, 1920; Venezuela, Dec. 17, 1920, and 25 Union of South Africa, Oct. 6, 1920), of which the following is a specification.

This invention relates to processes for cracking oils, particularly for the production of gasoline, but it is also applicable to 30 the production of other hydrocarbons lighter than the oil being cracked.

The invention has special reference to improvements in the method and apparatus described in my prior applications Serial Nos. 35 327,428, 327,429 and 327,430, filed Sept. 30, 1919.

My improved method of operation comprises subjecting to a cracking temperature a substantial body of heavy oil while in continuous flow through an upright still kept full of oil; the delivery of the heated oil to a separating chamber in which the vapors are separated from a body of hot oil maintained in said chamber; the continuous 40 return of residual oil from the separating chamber to the still through a carbon separating chamber, from which the carbon-free oil is delivered together with raw oil to the lower portion of the still, which is it- 45 self provided with means for removing any carbons adhering to the inner wall of the still. The carbon produced by the cracking is therefore constantly being removed from the circulating system.

55 I have discovered that in order to obtain

the best results it is desirable that the percentage of free carbon in the stream of circulating oil, as it is delivered to the still, be kept below 1% and preferably as low as .6 of 1%. 60

Further features of novelty are the manner in which the temperatures and conditions of condensation in the separating chamber and condensers are controlled whereby the method is made applicable to 65 the treatment of a wide range of oils and the conditions of operation during the progress of a run can readily be controlled.

The present arrangement renders the 70 whole process flexible and susceptible of successful application to oils of widely different physical and chemical properties.

The process is especially suited and applicable to the treatment of mineral oils of high boiling point, including crude 75 petroleums, shale oils, distillates, residual oils and others, for the production therefrom of light hydrocarbons such as gasoline and others suitable for use as fuel in internal combustion engines. It is operated at a pressure ranging from 60 to 120 pounds per square inch, and a temperature ranging from 700° to 850° F., depending upon the character of the oil to be treated. Experience shows that most oils yield the best results 80 when treated at a still pressure between 75 and 105 pounds per square inch, and a still temperature between 725° and 850° F. For example, Burk Burnett distillate is best treated at a still pressure of 86 pounds per square 85 inch and a still temperature of 745° F.; Eldorado, Kansas, distillate and fuel oil, at 86 pounds per square inch and a temperature of 755° F.; Pine Island crude at 86 pounds per square inch and a temperature of 780° F. 90

If oil vapor is allowed to accumulate above the body of oil in the still, the wide difference between the specific heat of the oil vapor and that of the oil causes a slow and irregular distribution of heat in the still. 100 As a consequence, local overheating and decomposition of the vapors are likely to occur. This results in excessive fixed gas loss and the formation of unsaturated and aromatic hydrocarbons. I have found that 105 these difficulties are avoided if the still is kept completely full of flowing oil and the oil is in constant circulation through the system. By giving the oil within the still a rotary motion about the axis of the still, 110

as by helical scrapers which remove carbon from the inner wall of the still, the distribution of the heat to the oil is rapid and uniform. The vapors tending to form within 5 the body of the oil move toward the axis of the still under the action of centrifugal force and are therefore enclosed in a protecting matrix of oil and are quickly removed from the still. Under these conditions local overheating is impossible, and 10 decomposition into fixed gases and unsaturated hydrocarbons from this cause is avoided.

One form of apparatus in which the process 15 may be carried out is illustrated in the accompanying drawings in which—

Fig. 1 is a diagrammatic representation of the plant as a whole;

Fig. 2 is a plan view of the adjustable 20 insulating section used on the separator,

Fig. 3 is a plan view of the screen in the coke trap,

Fig. 4 is a sectional view showing the interior arrangement of the coil and baffles in 25 the separator,

Fig. 5 is a plan view of the baffle plate, and

Fig. 6 is a plan view of the coil "d".

Referring to Fig. 1, A and A' are two 30 storage tanks for raw oil. From the bottom of the tanks, pipes 1 and 2 lead to the inlet side of a force pump P, which delivers the oil under the requisite pressure into the cold oil service tank B. From this tank, 35 valve controlled pipe-lines, a, b, c lead to coils f, e, d, located respectively in the separator S, and in the two pre-condensers PC and PC'. These coils d, e, f, while they may and preferably do act as pre-heaters 40 for the oil to be fed into the still, have as an important function, the control of the temperature in the particular condensers in which they are located. The coil d receives oil from the tank B from the pipes c and l, 45 and delivers hot oil through pipe u to the hot oil tank C. The coil e receives cold oil through pipe b and delivers hot oil through pipe t to the tank C.

Hot oil from tank C is delivered by an 50 injector I through pipe s together with oil from pipe n into the lower portion of the still St below the heated zone thereof. The still as shown, is mounted upright within a heating chamber F, provided with suitable 55 gas or oil burners 70. Preferably this chamber is subdivided into sections each having its own burner, with separate connections to the stack 71. The inlet pipe s and exit pipe 4 are located respectively below and above 60 the heating chamber.

The still is provided with a vertical shaft 6, carrying a helical scraper 8 driven by a worm gear 10. The scraper 8 engages the inside wall of the still and is driven in such 65 direction that the removed carbon may fall

downward toward the bottom of the still, from which it may be discharged through the exit pipe 12.

From the top of the still the heated oil flows through pipe 4 into the separator S 70 within which the liquid level is maintained at about the point indicated by the dotted line 14. The bottom of the separator is preferably conical and connected thereto is the discharge pipe 16 which opens into a 75 carbon or coke trap K. The pipe 16 has its opening below the screen 18 by which the carbon tending to float upward is separated. From the upper portion of the coke trap the oil now freed from carbon passes through 80 the pipe n into the pipe s wherein it is mingled with raw oil from the hot oil tank C and the mixture delivered to the still by an injector I.

The coke trap K is provided with a downwardly extending portion from which the precipitated carbon can be blown off through pipe 20.

The separator S is preferably provided with heat insulation which may entirely surround the body portion of the separator. Preferably this heat insulation is made in sections 22 each of which is made in sections as shown in Fig. 2 so that they can be applied or removed as required. 95

The separator is shown in detail in Fig. 4. As there indicated there is located above the normal oil level a grooved distributing plate 26 having perforations extending therethrough. Mounted above the distributor 26 100 is a deflecting plate 28 on to which may flow oil from pipes 30 and 32. Mounted above the deflecting plate 28 are a series of corrugated sheets 34 arranged closely adjacent to each other to provide a series of 105 narrow up and down passages therebetween. Above the plates 34 is a still further baffle arrangement 36 comprising plates arranged as shown to provide a tortuous passage for the ascending vapors. Above the baffle 36 110 is arranged the coil d and between the successive convolutions of the coil are arranged corrugated sheets 38 of Monel metal wire cloth. Supported on the convolutions are baffle plates 40 having perforations preferably arranged as shown in Fig. 5, the perforated plates being so arranged that the perforated portions are located alternately on opposite sides so that a further tortuous 115 passage is provided to bring the upwardly moving vapors into contact with the cooling coils. A still further baffle 37 may be used above the coil d. Any one or other suitable forms of baffle may be used to insure contact with ascending vapors and any 120 descending oil or condensate, the object being to obtain as complete rectification or 125 dephlegmation as possible.

Extending through the top is a spray nozzle m by which oil may be delivered into 130

the separator. This nozzle is connected to the pipe *l* which is in turn connected by branch *e*, to the pressure oil tank *B*; and also by pipe *k* to the heating coil *e* in the 5 pre-condenser *PC*. From the top of the separator *S* a vapor line *42* leads to the pre-condenser *PC*, from which in turn leads a vapor pipe *44* to the pre-condenser *PC'*. Valved connections *50* and *52* may be used 10 to directly connect the vapor lines *42* and *44* with the final condenser, *48*. From the pre-condenser *PC* the back run pipe *32* delivers into the separator and a similar back run pipe *30* is connected to the pre-condenser 15 *PC'*. Also connected to the pipe *30* is a valved pipe *52* connected to a source of air or gas supply, for a purpose to be described later. A gauge glass *72* connected by pipe *74* to the vapor line *42*, indicates the liquid 20 level in the separator *S*.

To the pipe *30* is connected a branch pipe *54* leading to the coke trap, and there is also provided a branch pipe *56* between pipes *32* and *54*, so that condensates can be run from 25 either of the pre-condensers to the upper portion of the coke trap, to be there mingled with the carbon-free oil on its way to the still.

Additional temperature control of the pre-condensers is obtained by delivering raw oil 30 through pipe *a* from tank *B* into coil *f* in pre-condenser *PC'*, thence into the hollow chamber *58*, pipe *60*, hollow chamber *62* into pipe *n'*, whence oil may flow through pipe 35 *p* into tanks *A* or *A'* or through pipe *δ* into a storage tank (not shown) to which is also connected a delivery pipe *64*. There may thus be delivered through this feed line either oil from tank *B* or from an outside 40 supply. It is preferable to use in this line, a high-boiling point oil, and if the particular oil under treatment contains relatively low boiling point constituents, it may be necessary to use a supply independent of the system. 45

66 and 68 are valved delivery pipes by which the condensates, in case they are products of desired composition, may be drawn off directly for use or further treatment. 50 70 is a valve at the end of the system. The desired pressure of the feed oil is obtained by pump *P* forcing oil into tank *B*. This tank *B* and the tank *C* are provided with pressure relief valves *h* and *j*, so that upon 55 development of excess pressure, oil is returned from these tanks to the storage tanks *A* and *A'*.

The various pipes are provided with valves at suitable points, these valves being 60 shown, but not referred to by specific numerals or reference letters.

The method is carried out as follows:

Oil is pumped from the receiving tanks into the still and heat is applied until the 65 requisite pressure is developed. This pres-

sure may be obtained by introducing air or gas through the pipe *52* into the pipe *30* leading into the interior of the separator.

The preliminarily heated oil from the tank *C* is delivered into the lower portion 70 of the still *St* wherein it is heated in its upward flow and delivered from the top of the still through the pipe *4* into the separator *S*.

The oil while being heated in the still is 75 subjected to the action of the centrifugal forces produced by the rotation of the carbon-removing helical scraper. The result of this centrifugal action is to cause the heated vapor charged portion of the oil to pass to 80 the center while the cooler oil is forced into immediate contact with the heated surface of the still, thus making the distribution of the heat in the body of the oil very rapid and uniform, and thoroughly protecting the 85 vapors from overheating and consequent decomposition with resulting development of undesirable hydrocarbons including an excess of fixed gases. When the oil in the still is raised to the cracking temperature, the 90 expansion of the liquid and formation of vapors cause an upward movement of the oil in the still and the vapors formed are carried upward and out of the heated zone within the body of oil which forms a protecting 95 matrix. This vapor charged oil is then delivered in a stream through the pipe *4* into the separator *S* at a point well above its bottom and discharged thereinto.

The inner wall of the still is kept free 100 from carbon by means of the helically shaped scraper *8* which delivers whatever carbon it may scrape off to the settling space at the lower end of the still below the inlet pipe *s*. This carbon scraper is similar to that described in my above mentioned applications. There are thus two carbon settling chambers formed at the lower end of the coke trap *K* and the still *St* respectively. 105

The heating of the oil in the still is thus 110 carried out under the very best conditions to avoid overheating of the vapors with the resulting formation of undesired and undesirable compounds.

The heated oil flowing from the top of the 115 still is delivered into the separator chamber which is an important and essential feature of my invention.

As has been above indicated the separator in its construction comprises a partially 120 heat-insulated vertical cylindrical chamber divided into a vapor space above, and a liquid oil space below. This vapor space is provided with a series of coils through which relatively cool oil is passed under control to cause a selective condensation of the vapors. This cooling oil may come directly from the tank *B* or may be oil which has been passed through the coil *e*; and a series of baffles to collect and precipitate the par- 125 130

ticles of condensate from the vapors not condensable at the temperature in the separator, and distributors to properly and evenly distribute the condensate over the 5 surface of bath of the hot oil in the lower part of the separator for the purpose of securing the most effective cracking action; and with means for admitting crude oil above the various baffles. The top of the 10 vapor space is, and a part of the walls may be, left exposed to the atmosphere to aid condensation.

The inlet pipes 30 and 32 provide for the return of the condensate from the first and 15 second pre-condensers to the separator and a cracking action results from the contact of these cooler oils with the highly heated bath of oils in the separator.

The functions of this separator are that it 20 provides a space for the vapors and vapor charged oils and particles, separate from the still itself, in which they are protected from direct heat and consequent super-heating and decomposition into unsaturated and aromatic hydrocarbons and fixed gases, and the waste resulting therefrom. It provides by 25 selective and controlled condensation a supply of suitable cooler oil which by the distributor is applied uniformly to the surface of the bath of hot oil in the lower part of 30 the separator, thus furnishing the most satisfactory conditions for cracking. The rate of condensation is controlled by controlling the rate of flow of oil through the coils; and by 35 exposing to the air varying portions of the upper part of the separator. The baffles in the separator remove the suspended and entrained particles of condensate from the uncondensed vapors and prevent them from 40 passing over to the subsequent condensers. By the close connection and rapid circulation from the still to the separator and on to the coke trap, the lower part of the separator contains a bath of oil which is maintained at substantially still temperature, thus 45 furnishing in the best possible form one of the necessary conditions for effective cracking without exposing the vapors to super-heating and decomposition.

Condensation in the upper part of the separator is necessarily accompanied by reduction of volume, and this means reduction of 50 pressure. Reduction of pressure is followed by expansion and release of vapors from the bath of oil. It will also cause the actual vaporization of particles of oil which were 55 potentially vaporized but held in liquid form by the pressure. This will renew the pressure. Thus there is in the separator an 60 extremely rapid pulsation or alternation of higher and lower pressure favorable to the cracking process. The separator is one of the units of the cyclic or U-tube circulation by which the oils are circulated, blended, freed 65 from carbon and alternately raised and low-

ered in temperature and returned fresh for further treatment, all of which steps play a part in this process of cracking.

By feeding fresh oil by a spray into the vapor space of the separator, a part of the 70 fresh feed oil is immediately vaporized without passing through the still, and the heavy less easily vaporized part is blended with the condensate formed in the upper part of the separator and thrown down upon the 75 surface of the hot bath of oil, furnishing another condition favorable to cracking by bringing into contact oils physically and chemically different.

Opportunity is thus afforded for returning 80 to the cracking bath from the pre-condensers one or more condensates of lower boiling point than those formed in the separator.

The whole process is flexible and susceptible of successful application to oils of 85 widely different physical and chemical properties. Most cracking processes are rigid and inflexible, susceptible of practically no modifications except those of temperature and pressure.

The separator also performs the function 90 of heat exchanger by which heat is taken from the vapors and imparted to the feed oil. This saves fuel.

The rate of flow of oil through the cooling 95 coils may be modified by the pump, or by the valve or by both.

The oil may be sent through the separator only, or it may be sent first through the first pre-condenser and there heated to a 100 considerable temperature before it enters the separator coils.

If desired the circulation through the separator coils may be omitted entirely, and condensation may be dependent upon the exposure of the top and walls of the vapor space.

Condensation may be produced or aided by spraying cold feed oil into the vapor space in 110 the separator.

By modifying and regulating the cooling and condensation the character of the oil thrown upon the cracking bath is correspondingly modified.

The vapors from the separator pass therefrom through pipe 42 into the pre-condensers. These pre-condensers are usually alike in construction and consist of vertical cylinders containing cooling coils and are surrounded by hollow chambers 58, 62, through 120 which oil or other cooling liquid may be circulated.

The pre-condenser PC is preferably provided with baffles which may be of any of the types shown in connection with the separator S. The second pre-condenser may or may not be baffled and is provided with a cooling coil which may or may not be connected with the feed system as previously explained. Both pre-condensers are pro- 125 130

vided with run back pipes by which the condensate formed in them may be sent to the separator or may be turned into the coke trap above the screen.

5 These pre-condensers have the following functions:

Selective condensation by means of which the proper condensates for the cracking process may be secured, and the undesirable 10 part may be returned to the circulation by way of the coke-trap.

The removal of all suspended vapor of high boiling point from the vapors which pass on to form the final product in the end 15 condenser.

The control of the end point of the final product through pre-condensing by means of the circulating oils of the cooling system.

They are heat exchangers removing heat 20 from the vapors and transferring it to the feed oils.

They also give elasticity and flexibility to the process, permit wide selection and distribution of the various products formed in 25 the process, and make possible a perfect control of the end point and other features of the final product.

They supplement the work of the separator.

30 If desired the product of these pre-condensers may be drawn off and used commercially for blending with casing head gasoline, etc.

With certain oils it may be desirable to 35 use only one pre-condenser, with others two may give best results. It is possible that oils may be encountered which could be best treated by connecting the separator with the vapor line to the main or final condenser.

40 The heated oil delivered from the still into the separator carries some carbon which it is essential to remove before the oil is returned to the still for re-cracking. This is effected in the coke trap K into which the

45 carbon charged oil is discharged from the bottom of the pipe 16 with a fairly rapid downward movement which tends to send the heavy carbon grains toward the bottom of the trap. The downward movement of the incoming oil is checked by the body of 50 stagnant oil while the carbon grains, having a higher specific gravity, are less retarded and sink down to the bottom of the trap.

The outlet from the trap is far above the 55 orifice of the pipe 16 so that there is a reversal of movement of the oil from the downward to the upward direction, this upward movement being extremely slow. By these means a deep zone of stagnant or 60 nearly stagnant oil of relatively low density and low viscosity is formed, from which the suspended carbon readily separates and a nearly complete precipitation of the carbon is thus effected. The screen 18 insures 65 that no suspended carbon in excess of the

desired limit is permitted to leave the coke trap and enter the still.

I have found that it is highly important that the suspended carbon in the oil delivered from the coke trap to the still shall 70 not exceed 1% and preferably be less than .6 of 1%.

On account of the agitation of the oil in the separator S due to the constant inflow from the still and the separation of vapors, 75 the free carbon carried over from the still or developed in the separator remains in suspension, but a large part of its has become massed into grains of appreciable size, which greatly facilitates its precipitation 80 into the coke trap below. The uncracked oil and the above mentioned condensates become thoroughly blended under the agitation in the separator S, said blended oil being of reduced density and in a highly 85 liquid condition on account of the light condensates therein. This fact facilitates the separation therefrom of the suspended carbon since the difference between the density of the oil and the carbon is increased, and 90 therefore, the momentum of the downward moving carbon in the trap forces it further than if it were contained in oil of greater density, and the settling of the carbon, through the action of gravity, is greater 95 because the oil is more liquid.

There are thus provided two points within the circulating system at each of which carbon is removed, namely the chamber at the lower portion of the still, and the coke 100 trap. These chambers form stagnant pools connected with the main circuit of the moving oil but in which there is substantially no motion. The carbon may be removed from these settling chambers either continuously 105 or intermittently as desired.

Following is a brief description of the commercial operation of the process in a 60-barrel still using Burk Burnett, Texas, oil.

The Burk Burnett crude used is a paraffin 110 base oil having a gravity Bé. of 39 to 41, and yielding approximately 40 per cent natural gasoline having an end point of 410° F., and about 16 per cent kerosene having a gravity of 42 to 44 Bé. The gasoline and kerosene are taken off by the usual methods. After this another 20 per cent is taken off 115 as gas oil and wax distillate, which constitutes the raw material for the cracking.

The pressure in the cracking still is kept 120 at 86 pounds per square inch, and the temperature in the still is held at 745° F. The temperature in the bottom of the separator runs 670° F., while that of the pre-condenser is 530° F. The temperature of the blended 125 oil returning to the still in pipe s, is 615° F.

The fixed gas loss is less than 1 per cent of the feed oil. The gasoline yield is between 78 and 79 per cent, by volume of the feed oil. The carbon is taken off in a sludge 130

like mass containing about 50 per cent carbon and 50 per cent oil, and measuring 20 per cent by volume of the feed oil. The carbon is separated from the oil and the oil 5 returned to the system. This 10 per cent of the feed oil yields, on cracking, 8 per cent additional gasoline, making the total yield of gasoline 86 to 87 per cent of the feed oil.

10 The gasoline has an initial point of 80° F. and an end point of 410° F., and a gravity of 58°-60° Bé. The content of unsaturated hydrocarbons does not exceed 3 per cent. The color is water white, and the odor is 15 like that of straight run gasoline. The vaporization curve is regular and constant. The gasoline requires no chemical treatment.

20 My invention provides a continuously operative method of cracking heavy hydrocarbons into lighter hydrocarbons, all the factors essential to the production of the desired end product being under perfect control.

25 25 The term gasoline as used in the specification includes lighter hydrocarbons of the motor fuel type.

I claim:

30 1. The process which consists in heating heavy hydrocarbon oil in continuous flow through a still to a cracking temperature; delivering the heated oil to a separator chamber wherein is maintained a pool of hot oil; permitting the vapors to separate from the 35 heated oil and collecting and condensing the same, delivering the oil from said pool to a carbon separator, delivering the cleaned oil from the carbon separator to the still; and keeping the amount of free carbon in the 40 cleaned oil below 1%.

35 2. The process which consists in heating heavy hydrocarbon oils in continuous flow through an upright still to a cracking temperature; delivering the heated oil from the 45 top of the still to the separating chamber wherein is maintained a pool of hot oil at a level above the still; permitting the vapors to separate from the oil and collecting and condensing the same; delivering the oil from the 50 said pool to a carbon separator, delivering the cleaned oil from the carbon separator to the lower portion of the still and keeping the amount of free carbon in the cleaned oil 55 below 1%.

55 3. The process which consists in heating heavy hydrocarbon oil in continuous flow through an upright still to a cracking temperature, removing separated carbon from the still, delivering the heated oil to a separator chamber wherein is maintained a pool of hot oil; permitting the vapors to separate from the 60 heated oil and collecting and condensing the same, delivering the oil from the said pool to a carbon separator, delivering the cleaned oil from the carbon separator 65

to the still; and introducing raw oil into the oil fed to the still.

4. The process as claimed in claim three in which raw oil is introduced into the vapor space of the separating chamber.

5. The cyclic process for the cracking of oils for the production of gasoline, comprising circulating oils in a closed system, comprising a heated still, separator chamber, and a carbon remover, whereby the oils are 75 brought to a temperature of potential vaporization in the still, the vapors are released in the separator chamber, the free carbon is removed from the oil in the carbon remover and the carbon freed oil is returned to the 80 still; maintaining a pool of hot oil in bottom of said separator chamber, conducting the separated vapors to a cooler chamber where the heavier vapors are condensed, supplying new oil to the system by passing said new oil 85 through coils in said cooler chamber; and delivering the condensate into said pool of hot oil.

6. The process which consists in heating heavy hydrocarbon oil in continuous flow 90 through a still to a cracking temperature, delivering the heated oil to a separator chamber wherein is maintained a pool of hot oil, permitting the vapors to separate from the hot oil, subjecting the vapors to rectification within the chamber, and then collecting and condensing the same, delivering the oil from said pool to a carbon separator, 95 delivering the cleaned oil from the carbon separator to the still, and introducing raw oil 100 into the oil fed to the still.

7. The process which consists in heating heavy hydrocarbon oil in continuous flow through a still to a cracking temperature, removing separated carbon from the still, 105 delivering the heated oil to a separator chamber wherein is maintained a pool of hot oil; permitting the vapors to separate from the heated oil and collecting and condensing the same, delivering the oil from said pool to 110 a carbon separator, delivering the cleaned oil from the carbon separator to the still; and introducing raw oil into the oil fed to the still.

8. The process which consists in heating 115 heavy hydrocarbon oil in continuous flow through a still to a cracking temperature, removing separated carbon from the still, delivering the heated oil to a separator chamber wherein is maintained a pool of hot oil, 120 permitting the vapors to separate, from the heated oil, subjecting the vapors to rectification within said chamber and then collecting and condensing the same, delivering the oil from said pool to a carbon separator, 125 delivering the cleaned oil from the carbon separator to the still, and introducing raw oil into the oil fed to the still.

In testimony whereof, I affix my signature.
RUSSELL D. GEORGE.
